[57] CLAIM

The ornamental design for a rear deck liner for Corvette automobiles, as shown.

DESCRIPTION

FIG. 1 is a top plan view of a rear deck liner for Corvette automobiles embodying my new design;
FIG. 2 is a front elevational view of the design of FIG. 1;
FIG. 3 is a rear elevational view of the design shown in FIG. 1;
FIG. 4 is a side elevational view of the design shown in FIG. 1 as viewed from the right; and
FIG. 5 is an enlarged cross-sectional view along lines 5—5 through the design shown in FIG. 1.
